[57] CLAIM

The ornamental design for a card shroud enclosure for an industrial computer, as shown and described.

DESCRIPTION

FIG. 1 is a right, top front perspective view of the card shroud enclosure for an industrial computer showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view of a second embodiment of our new design, the second embodiment differing from the first only in the details on the front surface;

FIG. 9 is a front elevational view of a third embodiment differing from the first only in the details on the front surface.

FIG. 1

FIG. 2

FIG. 3

FIG. 4

FIG. 5

FIG. 6

FIG. 7

FIG. 8

FIG. 9
